Filed Aug. 11, 1960, Ser. No. 61,699

Term of patent 14 years

(Cl. D9—6)

FIG. 1

FIG. 2

FIG. 4

FIG. 1 is a top plan view of a bath mat or similar article, embodying my new design.

FIG. 2 is a cross sectional view thereof taken along lines 2—2 of FIG. 1;

FIG. 3 is a bottom plan view thereof; and

FIG. 4 is an enlarged fragmentary view of the upper left corner of FIG. 3.

Except for the central area in FIG. 1, which is plain, it is to be understood that the elements illustrated on part of the areas in FIGS. 1 and 3, cover the entire areas shown.

I claim:

The ornamental design for a bath mat or similar article, substantially as shown and described.
